RELIGIOUS LAMP

Le Roy F. Anderson, Camarillo, Calif.

Application February 19, 1954, Serial No. 29,127

Term of patent 7 years

(Cl. D48—20)

FIG. 1

FIG. 2

To all whom it may concern:

Be it known that I, Le Roy F. Anderson, a citizen of the United States, residing in the city of Camarillo, county of Ventura, and State of California, have invented a new, original, and ornamental Design for a Religious Lamp, of which the following is a specification, reference being had to the accompanying drawings, forming a part hereof.

Fig. 1 is a top plan view of a religious lamp embodying my new design;

Fig. 2 is a front elevational view;

Fig. 3 is a side elevational view looking at the right of Fig. 2;

Fig. 4 is a side elevational view looking at the left of Fig. 2, the drawer being shown in open position; and

Fig. 5 is a rear elevational view.

I claim:

The ornamental design for a religious lamp, substantially as shown.
